UNITED STATES PATENT OFFICE.

JOHN L. McCULLOUGH, OF BROOKLYN, NEW YORK.

ELECTRICAL FIREARM.

SPECIFICATION forming part of Letters Patent No. 514,491, dated February 13, 1894.

Application filed April 7, 1893. Serial No. 469,417. (No model.)

To all whom it may concern:

Be it known that I, JOHN L. McCULLOUGH, a citizen of the United States, and a resident of the city of Brooklyn, in the county of Kings 5 and State of New York, have invented certain new and useful Improvements in Fire-arms, of which the following is a specification.

This invention relates to the class of fire arms wherein the ignition is effected by an 10 incandescent wire or filament when an electric circuit is closed. In carrying out the invention I adapt this mode of ignition to a magazine gun.

The invention will be fully described here- 15 inafter and its novel features carefully defined in the claims.

In the accompanying drawings I have illus- 20 trated an embodiment of my invention.

Figure 1 is a vertical longitudinal mid-section of the main or lock portion of a gun constructed according to my invention. Figs. 2 and 3 are vertical longitudinal sectional views, in different planes, of a portion of the gun nearer the muzzle thereof than the section 25 in Fig. 1. Fig. 4 is a horizontal section taken substantially in the broken plane indicated by line IV, IV, in Fig. 1; and Fig. 4^a is also a horizontal section in the plane of line IV^a—IV^a, in Fig. 10. Figs. 5, 6, 7, 8, 9 and 10 30 are, respectively transverse sections taken in the planes indicated by the lines V—V, VI—VI, VII—VII, VIII—VIII, IX—IX and X—X, in Figs. 1 and 2. Fig. 11 is a plan view of a part of the operating slide. Fig. 12 is a horizontal section taken in the plane of the axis 35 of the chambered carrier. Fig. 13 is a perspective view of the sliding breech-block, detached. Fig. 14 is an enlarged perspective view showing the construction of the cutter- 40 tube and the cutter for puncturing the butt of the cartridge-shell. Fig. 15 illustrates the construction of the cartridge. Fig. 16 is a longitudinal section of the loading and extracting plunger on an enlarged scale, detached. Fig. 17 is a general view on a small scale of 45 the gun and its battery.

1 represents the metal frame and casing which incloses the principal operative mechanism of the gun and connects the stock (not 50 shown) with the barrel, 2.

In vertically arranged keepers in the frame is mounted a partition plate 3, which carries

a pin, 4, on which is mounted a chambered cylindrical carrier, 5. This construction is clearly shown in Fig. 12. The carrier 5 (seen 55 in end elevation in Fig. 9) is slipped on the pin 4, and the carrier and plate 3 slipped down into the casing 1, before the top-plate of the casing is secured thereon.

Under the barrel 2, is situated the magazine, 6, which is of the usual tubular form. This magazine, as herein shown, will be aligned with one of the four chambers, 5^a, in the carrier when another one of said chambers is at the index point, or in line with the bore in 65 the barrel 2.

Back of the plate 3, in the casing, is a sliding breech-block, 7, which plays to and fro in keeper-guides, 1^a in the sides of the casing 1. This block 7 carries two plungers, one of 7c which registers with the chamber 5^a in the carrier 5 which is at the index point, and the other with one of the side chambers 5^a, that is, the one which contains the empty shell and which was last at the index point. This 75 last is the ejecting plunger, 7^a, seen in Fig. 12. The former is the loading plunger, 8, seen in Figs. 1, 4 and 16; it serves to drive the cartridge (x in Figs. 1 and 4) from the chamber in the carrier into the cartridge 80 chamber in the barrel, and also, on its back stroke or movement, to withdraw the empty shell from the barrel into the chambered carrier. The peculiarities of this plunger 8 will be more minutely described hereinafter. 85

9 is the operating slide, mounted to play in guides longitudinally of the barrel, and below the magazine. This slide 9 is in the form of a tube, but it has a plate, 9^x, secured to its crown, as clearly seen in the cross-section in 90 Fig. 9. This plate, which is really a part of the slide proper, does not extend the entire length of the tubular part. On the operating slide is fixed a grip, 9^{xx}, of the usual kind, for moving the slide to and fro in loading. The 95 plate 9^x of the operating slide is seen in plan in Fig. 11. It engages and operates the sliding block 7, through the medium of pendent lugs 7^b (see Fig. 13) on the block which engage between lateral shoulders 9^b, on the plate 9^x. In order that the operating slide may move back to some extent at first without the block 7 partaking of this movement, I make the lugs 7^b on the block narrow

100

as compared with the space between the shoulders 9^b (see Fig. 11) on the plate 9^x. The reason for this will be hereinafter explained.

The construction of the plunger 8 is best illustrated in Fig. 16, where it is represented as formed integrally with the block 7, as it may be. This plunger is tubular, and when the sliding block 7 is at the end of its forward movement (as in Figs. 1 and 4), the forward end of the plunger embraces the cartridge shell for a considerable part of its length. Within the tubular body of the plunger is a cutter-tube, 8^a, fixed in position in the axis of the plunger. This cutter-tube (see Fig. 14) bears on its front end an angular cutter, 8^b, which is adapted to be driven through the thin metal which closes the butt of the cartridge shell. Exterior to the cutter-tube 8^a, and embracing the same within the tubular plunger, 8, is a tube 8^c, which is free to slide to and fro with the latter.

When the parts are assembled as in Figs. 1 and 4, a lug, 1^b, on the cap-plate of the casting 1, depends into a slot, 8^d, in the tubular plunger 8, and takes behind the rear extremity of the tube 8^c, whereby when the plunger 8 is retracted, it carries the empty cartridge shell back with it until the shell is fairly lodged within the chamber in the carrier 5; but at this moment the rear end of the tube 8^c strikes the lug 1^b and is arrested, and in its further backward movement, (the shell being arrested by the tube 8^c), the plunger 8 frees itself and draws away from the shell, leaving it in the carrier. I may say here, that the shell of the cartridge (see Fig. 15) has no flange, and its end-plate being slit by the cutter 8^b, it will be expanded and flared slightly at its butt by the explosion of the charge; and I utilize this expansion to fit it in the embracing end of the tubular plunger 8 with sufficient stability to insure the shell being extracted. To effect this, I enlarge the inner diameter of the plunger at the point where the base or butt of the shell is situated when the charge is ignited, and the shell is expanded into this enlargement, which is clearly shown at 8^e in Fig. 16. After the sliding block 7 and its plunger 8, have been drawn back far enough to lodge the shell in the indexed chamber of the carrier 5, the latter will be rotated, by the further backward movement of the operating slide, through the medium of a stud, 10, on the plate 9^x. This stud imparts a small portion of the rotation necessary to bring the next chamber in the carrier to the index point, the main portion of the movement being effected by a stud, 10^x, in said plate on the next forward motion of the operating slide. This device for rotating the carrier is substantially the same as that embodied in my pending application Serial No. 454,925, and I do not claim it herein. Indeed my present invention is not limited to any specific means for rotating the carrier. I need only say that the carrier has straight and oblique grooves, as seen in the dotted

lines in Fig. 11, along which the non-aligned studs 10 and 10^x play. After the operating slide has been drawn or moved back to its full extent, it is pushed forward again; the plunger 8 drives the cartridge at the index point into the barrel, and the ejecting plunger drives the empty shell out of the carrier. When the plunger drives the cartridge "home," the cutter or blade at the extremity of the cutter-tube within the hollow plunger, penetrates the thin metal at the butt of the shell and thus exposes the powder so that it may be ignited.

I will now describe the means I employ for igniting the charge by pulling the trigger, promising that when the trigger is pulled it locks the block 7 against the recoil, advances a platinum loop through the tubular plunger 85 until it is in contact with the powder, and then closes an electric circuit through said loop to produce incandescence.

11 is the trigger, which is somewhat in the form of an inverted L, or bell-crank, being 90 fulcrumed in the frame 1 at 11^a (Fig. 1). The lower extremity of the trigger depends in the usual manner into the trigger guard, and the upper, nearly horizontal arm, 11^x, thereof, extends forward and stands, normally, just above a rear extension, 7^a, on the upper part of the block 7. Thus, when the trigger is pulled, this arm descends until its free extremity takes behind the said extension and prevents the recoil of the block.

11^b is the trigger spring.

Within the cutter-tube 8^a, and co-incident with the axis of the tubular plunger 8, is a rod, 12, of some suitable refractory material, which has an endwise movement through the plunger and the block 7. This rod may be made from indurated fiber, which is a non-conductor, and it has embedded in its mass two conducting wires which are electrically connected, at the forward end of the rod, by 110 a loop 13, of platinum wire. At its rear end, where it projects from the bore in the sliding block 7, it is attached to a cross-bar, 12^x, the extremities of which rest in forks in the upper ends of the arms of a rocking frame, 14, 115 which rocks in bearings, 15, on the block 7.

Extending through the tubular part of the operating slide 9, is a rod, 16, which is coupled to the trigger 11 at 16^x, and has a cross-bar, 16', which takes in front of the lower extremities of the arms of the frame 14, below the rocking bearings of said frame. When the trigger is pulled, the rod 16 is drawn back, thus rocking the frame 14, and moving the rod 12 forward in the plunger 8 until the platinum loop, 13, enters the slit cut in the cartridge shell and comes into contact with the powder of the charge. At this moment,—that is, at the moment the rod 12 reaches the end of its forward movement, the circuit will 125 be closed through the loop 13, and the charge ignited. I will now describe how this is effected.

Under the barrel 2, forward of the grip 9^{xx},

is a housing 17, secured to the barrel, and the front end of this housing is closed by a block or plate, 17^x, which I prefer to make of insulating material. The front end of the tubular operating slide 9, and of the rod 16, play in this housing. Two conductors, 18 and 19, lead from the respective poles of a conveniently located battery or generator 20 (see Fig. 17) to the block 17^x (see Figs. 2, 3 and 8). The conductor 18 (Fig. 2) connects electrically with a spring contact finger, 18^x, which rests on, and is always in contact with the raised or enlarged front end or extremity 16², of the rod 16. The conductor 19 (see Fig. 3) is connected with a long spring contact finger, 19^x, which extends back in the housing 17 and bears constantly, at its free end, on a contact plate, 19' (see Fig. 10) set in the crown of the tubular operating slide 9, and insulated from said slide. Within the tubular slide 9, is an insulated conductor 19², which connects at its front end with the plate 19', and at its rear end with an insulated contact plate 19³ (see Fig. 11), on and carried by the plate 9^x, and insulated therefrom. This plate 19³, is connected electrically with one branch of the platinum loop 13, through the medium of a contact spring 19⁴, one branch of which rests on the plate 19³ and the other branch bears on the pendent terminal of a conductor, 19⁵, which extends through the rod 12 (see Fig. 16), connecting at its front end with one branch of the loop 13. Within the tubular slide 9, is another insulated conductor 18² which is connected at its front end (Figs. 2, 4^a, and 10) with a contact finger, 18', secured to the tubular extremity of the slide 9, its free end being normally out of contact with the rod 16. The conductor 18², is connected at its rear end with an insulated contact plate, 18³ (see Fig. 11) arranged alongside of the plate 19³, on the plate 9^x. This plate 18³, is connected with the other branch of the platinum loop 13, by means of a contact spring 18⁴, precisely like the spring 19⁴, and placed by the side of the latter. The upper branch of this spring 18⁴ bears on the pendent terminal of a conductor 18⁵ (see Fig. 16) which extends through the rod 12, and connects at its front end with a branch of the platinum loop 13. Normally, the break in the electric circuit is in the housing 17, where the finger 18' is out of contact with the rod 16. When the gun is ready for firing, as in Fig. 1, the operator pulls the trigger. This has the effect to drive the rod 12 forward until the platinum loop 13 is in contact with the powder; and it also has the effect to draw back the rod 16. At the termination of the movement the rounded shoulder 16³ on the forward end of the rod 16, is brought into contact with the spring finger, 18', which serves to close the circuit the current then flowing freely through the rod 16 between the fingers 18^x and 18'. When the operating slide 9 is drawn back in loading, the contact plates 18³ and 19³ are drawn back and out of contact with

the respective contact springs 18⁴ and 19⁴, so that it will be impossible for the current to flow through the platinum loop while the parts are in this position. This latter feature is not, however, really essential. The contact springs 18⁴ and 19⁴, being arranged side by side, do not both appear in Fig. 1, the spring 18⁴ completely obscuring the other. These springs are herein shown as of bell-crank form and mounted on the pivot pin of the frame 14, but insulated therefrom and from each other, of course. When the circuit is closed the current flows from one pole of the generator through the conductor 18, to the finger 18^x, thence through rod 16 to contact finger 18', thence through conductor 18² to plate 18³, thence through spring 18⁴ to conductor 18⁵, thence to and through the platinum loop 13 to conductor 19⁵, thence through spring 19⁴ to contact plate 19³, thence through conductor 19², thence to the plate 19', thence through contact finger 19^x to the conductor 19, and thence back to the other pole of the generator. The generator may be a battery 20, and when the gun is used for target purposes it may be placed conveniently near and connected to the gun by the conductors 18 and 19, as clearly shown in Fig. 17. For this purpose, these conductors may be of tinsel 95 cord and these cords may be loosely twisted together. Several guns may be thus connected with a single generator, the cords being of sufficient length to permit the free use of the guns.

It is not really necessary to enlarge the front end of the rod 16; any form of shoulder on the rod to contact with the finger and close the circuit, will serve. Indeed the particular construction of this part of the gun is not essential to the invention.

I have stated that the operating slide has a certain amount of movement which is not partaken of by the sliding block 7. The purpose of this is to allow the operating slide, on its outstroke, to rotate the chambered carrier before the sliding block starts forward. Of course, if room were provided in the casing, the block 7 might move back as far as the slide, but this would extend the casing unduly, and it is not at all necessary.

Having thus described my invention, I claim—

1. In a breech-loading fire-arm, the combination with a chambered carrier for the cartridge, of a reciprocating tubular plunger adapted to play through the chamber in the carrier and drive the cartridge therefrom into the cartridge chamber in the barrel, said plunger being provided at its front end with an extractor and a cutter to pierce the butt of the cartridge-shell, and means substantially as described for igniting the charge by a pull on the trigger of the piece, as set forth.

2. In a breech-loading gun, the combination of a chambered carrier for the cartridge, of a reciprocating tubular loading plunger for

driving the cartridge from the carrier into the cartridge chamber of the barrel, said plunger being provided at its front end with an extractor and a cutter for piercing the butt of the cartridge-shell, a reciprocating rod 12, in said loading plunger, a loop 13, carried by said rod, an electric circuit of which said loop forms a part, and means, substantially as described whereby a pull on the trigger of the piece advances said loop into contact with the charge and closes said electric circuit, as set forth.

3. In a breech-loading fire-arm, the combination with the chambered carrier for the cartridges, of a sliding block 7, arranged behind the carrier and provided with a loading plunger, means for reciprocating said block, and the trigger 11, provided with a forwardly projecting arm 11^a, the free end of which descends behind said block 7, when the trigger is pulled and serves to resist the effect of the recoil on the block, as set forth.

4. In a breech-loading fire-arm, the combination with the chambered carrier for the cartridge, the reciprocating block 7, back of the carrier and provided with a tubular loading plunger 8, furnished with a cutter, the loop-carrying bar 12, in the plunger 8, and coupled to a rocking frame 14, means substantially as described for rocking said frame when the trigger 11 is pulled, and the said trigger provided with a forwardly projecting arm 11^a, arranged to take behind the frame 14 when the trigger is pulled and resist the effect of the recoil on the rod 12, as set forth.

5. In a breech-loading fire-arm, the combination with the chambered carrier for the cartridges, and the tubular, reciprocating, loading plunger, 8, provided with an enlargement, 8^a, near its front end for the cartridge-shell to expand into when the charge explodes, and with a cutter for piercing the shell, of means

substantially as described for igniting the charge by electricity, as set forth.

6. In a breech-loading fire-arm, the combination with a tubular loading plunger for driving the shell into the cartridge chamber of the barrel, a cutter carried by the plunger for piercing the cartridge shell, and means for operating said plunger, of a loop 13, a carrier therefor arranged within the plunger, an electric circuit of which said loop forms a part, a trigger, and means intermediate the trigger and the loop-carrier whereby the loop is moved into contact with the charge, and the electric circuit closed, by pulling on the trigger, as set forth.

7. In a breech-loading fire-arm, the combination with the tubular loading plunger 8, provided with the angular cutter, 8^a, near its forward end, of an electric circuit, a loop 13, forming a part of said circuit, a carrier for said loop, and means intermediate the trigger and loop-carrier whereby when the trigger is pulled the loop will be moved forward within the cutter, as set forth.

8. The combination with a fire-arm adapted for discharge by electricity, of an electric charge igniting circuit partly inclosed within the casing of the fire-arm and partly without said casing, and having a circuit-closer within the receiver and a generator in said circuit, said generator being detached from the fire-arm and connected electrically therewith through the medium of flexible conductors, as set forth.

In witness whereof I have hereunto signed my name in the presence of two subscribing witnesses.

JOHN L. McCULLOUGH.
